UNITED STATES PATENT OFFICE

163,630

HOLDER FOR THE LIDS OF POTS AND PANS

Sylvia Starr Pollock, Mayville, N. Y.

Application December 11, 1948, Serial No. 150,109

Term of patent 3½ years

(Cl. D44—29)

To all whom it may concern:

Be it known that I, Sylvia Starr Pollock, a citizen of the United States, residing at Mayville, in the county of Chautauqua and State of New York, have invented a new, original, and ornamental Design for a Holder for the Lids of Pots and Pans, of which the following is a specification, reference being had to the accompanying drawing, forming part thereof; and in which,

Fig. 1 is a perspective view of a holder for the lids of pots and pans showing my new design; and Fig. 2 is a front elevational view thereof.

I claim:

The ornamental design for a holder for the lids of pots and pans, substantially as shown.

SYLVIA STARR POLLOCK.
